Specification for Design.

Patented June 18, 1918.

Application filed February 7, 1918. Serial No. 215,912. Term of patent 14 years.

● **To all whom it may concern:**

Be it known that I, RALPH A. SCHOENBERG, now by judicial change of name RALPH A. BELMONT, a citizen of the United States, residing at New York, in the county and State of New York, have invented a new, original, and ornamental Design for a Casing for an Electric Switch, of which the following is a specification, reference being had to the accompanying drawing, forming part thereof, in which—

Figure 1 is a top plan view of a casing

for an electric switch illustrating my new design.

Fig. 2 is an elevation;
Fig. 3 is a side elevation; and
Fig. 4 is a bottom plan thereof.

What I claim is:

The ornamental design for a casing for an electric switch, as shown.

RALPH A. SCHOENBERG.
